UNITED STATES PATENT OFFICE.

JOSEPH GROVE, OF SPARKHILL, BIRMINGHAM, ENGLAND, ASSIGNOR TO FREDERICK MOUNTFORD, OF BIRMINGHAM, ENGLAND.

CARBURETER.

1,159,933.

Specification of Letters Patent.

Patented Nov. 9, 1915.

Application filed April 30, 1914. Serial No. 835,568.

To all whom it may concern:

Be it known that I, JOSEPH GROVE, a subject of the King of Great Britain, residing at 627 Stratford road, Sparkhill, Birmingham, England, have invented certain new and useful Improvements in and Relating to Carbureters for Internal-Combustion Engines, of which the following is a specification.

10 This invention relates to carbureters for internal combustion engines of the type in which provision is made for preliminary heating of the fuel and is particularly useful for heavy oils.

15 The principal object of the invention is to provide improved means for effecting the preliminary heating and vaporization of the oil when starting the engine as well as during normal running and to control conveniently the flow of fuel past or through the heating devices.

20 In the accompanying drawings Figure 1 shows, partly in section, a general elevation of one form of carbureter constructed according to the invention, and Fig. 2 shows, in section, a modification. Fig. 3 is a perspective view of the homogenizer.

25 Referring first to Fig. 1 a casing *a* is formed at its upper end with a carbureting chamber *b* and at its lower end with a chamber *c* which contains the homogenizer *d*.

The carbureting chamber *b* is preferably provided with inclined sides converging toward the lower end and terminating in a 30 comparatively small orifice *e* leading centrally into the top of the homogenizing chamber *c*. The air is admitted at the top of the carbureting chamber *b* through a valve *f* hereinafter more fully described and 35 the oil is admitted through a suitable nozzle *g* projecting into the carbureting chamber *b* so that the oil escapes at or near the center thereof.

40 The oil fuel is supplied from any convenient source as, for example, an ordinary float-feed regulating device *h*. Connection of the carbureter and float-feed tank may be effected by a side flange *i* on the part *a* and a similar flange on the part *h*. The oil nozzle 45 *g* projects through the flange *i* and casing *a* horizontally into the carbureting chamber *b*.

50 The top of the carbureting chamber is covered by a plate *m* carrying the spring-controlled valve *f* for admitting air. Such

valve is preferably centrally arranged on the 55 underside of the plate *m* and adapted, when moved upward by the spring *n*, to close the apertures *o* in the plate *m*. The spring *n* is arranged between the top of the plate *m* and a collar or the like *p* at the upper end of the 60 valve spindle.

A cylindrical closed casing *q* is secured to the aforesaid cover plate *m* and is provided at its upper end with apertures *r*, the effective area of which is adapted to be adjusted 65 by a rotatable plate *s* mounted on said casing and having corresponding apertures as shown. The rotatable plate *s* is held in its adjusted position by any convenient means, and adjustment may be effected by an arm *t*. 70

The homogenizing chamber *c* is cylindrical being open at the bottom for the insertion of the homogenizer *d* and has the comparatively small central opening *e*, above referred to, at its upper end. 75

The homogenizer is of a mushroom shape and provided with a lower plate *u* adapted to cover the lower end of the homogenizer space when the homogenizer is inserted in position. This lower plate is provided with 80 a large number of small holes which are conical in shape and taper upwardly.

The upper part *d* of the homogenizer is connected to the lower plate *u* by a central stem *v* and the peripheral edge of the said part *d* fits the casing. Such edge is provided with a number of small inclined grooves *w* through which a part of the mixture passes and is thereby thoroughly broken up and mixed. The upper part of the 90 homogenizer is conical in shape leaving a small flat top *x* which comes opposite the opening *e* and is situated a slight distance therefrom.

A large number of holes *z* are provided in 95 the upper part of the homogenizer, such holes being preferably drilled at about right angles to the conical surface and being formed smaller at their lower ends than at the top ends. 100

The casing *a* forming the carbureting chamber and homogenizing chambers is adapted to be secured on to the top of another casing *3* provided with a three-way valve *4*. The mixture after passing through 105 the homogenizer passes into the top of this casing and then, normally, passes by way of a branch *5* through a tube heated by the ex-

2
haust gases of the engine in any convenient manner. Such heating device is not shown but is of any suitable construction and is connected at one end to the branch 5 and at 5 the other end to the branch 6. After passing through this heater the mixture is returned by way of said branch 6 and is led to an opening 7 between the valve 4 and the chamber of the throttle valve, the latter being secured to the flange beneath the opening 7. The valve 4 is so constructed that by 10 rotating the same through about a quarter turn the outlet 5 is cut off and the upper part of the valve casing put into direct communication with the throttle valve chamber 15 through the port 8. By this means the mixture can be admitted direct to the engine.

In the position of the valve 4 intermediate to the two above referred to, the valve permits mixture to pass to the engine partly 20 through the passage 5 and partly through the passage 8.

A branch or auxiliary opening may be provided between the three-way valve and 25 the throttle valve chamber for the admission of additional air, such opening being controlled by a spring pressed valve. In the device illustrated this valve is arranged at 9 and is controlled by a spring 10. The air is 30 admitted through ports 11 which can be adjusted by a rotatable ring 12.

For producing the required vaporization when the engine is cold and enabling the engine to be conveniently started, provision is 35 made between the parts 7 and 8 for the reception of an electrical heater. The latter comprises a wire coil 13 carried on an insulating core and connected to any convenient external terminals.

40 To cause the mixture to pass in close contact with the heating coil the latter is incased by a short tubular member 14 through which the mixture must pass. The provision of this member 14 is of great importance, inasmuch as the mixture will be maintained in contact with the heater throughout the greater portion of the length of the latter before it can escape from the ends of the member and thereby insure rapid and 45 thorough heating of the mixture. In other words, the member constitutes a retarder to impede the escape of the mixture to insure its adequate heating. This device may be heated by a battery, or by an electrical machine driven by the engine, or by hand.

50 When starting the engine the valve 4 is caused to direct the mixture through the passage 8. In passing thence to the engine it is effectually heated by the coil and 55 brought to the required condition for explosion in the engine cylinder. After the engine has been running for a few minutes the heater 13 can be cut out of action and the mixture diverted through the passage 5 for 60 heating by the exhaust gases as above de-

scribed. Two or more electrical heating coils may be used, and such coil or coils may be used for temporary purposes while the engine is running, a part of the fuel being then directed through the passage 8.

70 Instead of a single exhaust or engine heating tube as above described, two or more of such heated tubes may be employed of comparatively small internal diameters, arranged in serial order, singly, or in pairs, or 75 according to requirements. Each tube would have a corresponding inlet port arranged so that the operation of the control valve uncovers the ports one after the other, or consecutively. With this arrangement 80 the control valve performs an additional function of a throttle valve whereby the ordinary throttle valve generally employed may be dispensed with. One form of such an arrangement is illustrated in Fig. 2 85 wherein the inlet ends of three loop-shaped tubes 15, 16, and 17 are shown. The tubes are of gradually increasing diameter, the tube 15 being the smallest and the tube 17 the largest. As an example, with engine 90 cylinders of $3\frac{1}{4}$ " diameter, the internal diameters of the tubes may be $\frac{1}{8}$ ", $\frac{1}{16}$ " and $\frac{1}{4}$ " respectively. The three heater tubes are secured, as by a flange 18, to one side of the casing 3 which is provided with inlet ports 95 19, 20 and 21 corresponding to the tubes.

The valve 4 is in this case of segmental shape in cross-section. With the valve in the position indicated in full lines, which is the position for starting, the mixture passes 100 from the homogenizing chamber past the valve, through the port 8 and around the coil 13 to the engine. When the valve is moved to the position indicated by the thick dotted lines γ all the inlet ports 19, 20 and 105 21 are open and the mixture passes direct from the homogenizing chamber through the pipes 15, 16 and 17 and returns to the casing 3 through the connection 6. This position is the full power position. When it is required to stop the engine, the valve is moved to the position indicated by the thin dotted lines α when communication from the homogenizing chamber is cut off. It will be understood that when the engine is running 110 light and for slow speeds the smallest port 19 only is opened. For higher speeds and power one or more of the ports would be opened accordingly.

115 Although the arrangement of ports and vaporizing tubes is described above as specially applicable to carbureters of the type referred to, it will be seen that this system is applicable to other heavy oil carbureters.

120 For starting the engine from cold with heavy oils, two electric heating devices similar to 13 may be connected in series. The second device is indicated by 13 in Fig. 2.

125 Having now particularly described and ascertained the nature of my said invention 130

and in what manner the same is to be performed, I declare that what I claim is:—

1. In an internal combustion engine, the combination with a carbureting chamber, of 5 a primary electrical heater, a secondary exhaust heater, a valve arranged between the carbureting chamber and the primary heater and operating to control the passage of the explosive mixture to either of the heaters, 10 and means for retarding passage of the explosive mixture past the primary heater in the direction of the length of the latter.

2. In an internal combustion engine, a carbureter, a valve-casing communicating 15 therewith, an open-ended housing having a port opening into the valve casing, an electrical heating coil disposed within the housing and out of contact with the walls thereof to permit passage around the coil of the explosive mixture, and means for retarding 20 passage of the explosive mixture past the primary heater in the direction of the length of the latter.

3. In an internal combustion engine, a carbureter, a valve casing communicating 25 therewith, an explosive-mixture receiving chamber constituting an extension of the valve casing, a coil unit having one end coupled with the valve casing and its other end discharging into the receiving chamber and having a portion of its length disposed with- 30 in the exhaust pipe to constitute a heater for the engine, an open-ended housing arranged within the receiving chamber and having a port opening into the valve casing, an elec- 35

trical heater disposed within the housing and out of contact with the walls thereof to permit passage of the explosive mixture around the heater in the direction of its length, and a valve in the casing arranged to 40 control passage of the explosive mixture at will either to the coil unit or to the housing.

4. In an internal combustion engine, a carbureter, a valve-casing communicating therewith, an explosive-mixture receiving 45 chamber constituting an extension of the valve casing, a coil unit having one end coupled with the valve casing and its other end discharging into the receiving chamber and having a portion of its length disposed with- 50 in the exhaust pipe to constitute a heater of the engine, an open-ended housing arranged within the receiving chamber and having a port opening into the valve casing, an electrical heater disposed within the housing and out of contact with the walls thereof to permit passage of the explosive-mixture around the heater in the direction of its length and a valve in the casing arranged to 55 control passage of the explosive-mixture at will either to the coil unit or to the housing and means independent of the carbureter for supplying air to the receiving chamber at the point of discharge of the heated mixture.

In testimony whereof I affix my signature 60 in presence of two witnesses.

JOSEPH GROVE.
